CLAIM

The ornamental design for a skin diagnosis device, as shown and described.

DESCRIPTION

FIG. 1 is a top right front perspective view of the skin diagnosis device;

FIG. 2 is another top right front perspective view of the skin diagnosis device of FIG. 1;

FIG. 3 is a bottom right front perspective view of the skin diagnosis device of FIG. 1;

FIG. 4 is a rear right perspective view of the skin diagnosis device of FIG. 1;

FIG. 5 is a front elevational view of the skin diagnosis device of FIG. 1;

FIG. 6 is a rear elevational view of the skin diagnosis device of FIG. 1;

FIG. 7 is a left side elevational view of the skin diagnosis device of FIG. 1;

FIG. 8 is a right side elevational view of the skin diagnosis device of FIG. 1;

FIG. 9 is a top plan view of the skin diagnosis device of FIG. 1; and,

FIG. 10 is a bottom plan view of the skin diagnosis device of FIG. 1.

1 Claim, 10 Drawing Sheets
